UNITED STATES PATENT OFFICE.

CARL NASKE, OF BERLIN-CHARLOTTENBURG, GERMANY.

KILN FOR THE BURNING OF CEMENT.

Application filed February 7, 1925, Serial No. 7,629, and in Germany January 8, 1924.

This invention has reference to automatic upright kilns or shaft furnaces for the burning of cement, and it is intended to generally improve the utilization of the heat

5 and to facilitate the operation and increase the output of available product. In the previous art means have been disclosed for the purpose of injecting the finely ground material under treatment together with the 10 fuel, particularly gas, either in the horizontal direction into a substantially horizontal chamber or vertically downwards into an upright chamber. In this operation the intensity of the flame is so adjusted that the 15 particles of the material to be burnt are injected into one section of a bipartite heat accumulator or regenerator, where they become deposited and, together with the waste 20 gases, yield the heat still contained therein to the heat accumulator or regenerator. After one section of such regenerator or the like, as disclosed in the previous art, has been heated in the manner described, the other section thereof is heated after the reversal 25 of two rotating valves or dampers, while the air of combustion is now aspirated through the first mentioned section and is there preheated.

With this manner of operation the air 30 of combustion after the reversal of the valves is first heated to a comparatively high temperature, and subsequently in consequence of increasing cooling of the particular section of the regenerator the heating gradually diminishes, so that the utilization of the waste heat is gradually impaired. It therefore becomes necessary to constantly change the admission of fuel, so that it will be practically impossible to obtain a thoroughly uniformly 35 burnt kind of goods by means of the previous apparatus, though this is a point of chief importance not only in the case of cement, but also with all other kinds of material to be calcined. Besides, the 40 highly heated burning chamber is only incompletely utilized for the preheating of the air of combustion; nor can it be used for the frequently desired subsequent sintering of the material to be calcined.

45 The invention has for its object to obviate and overcome the difficulties referred to in connection with kilns or shaft furnaces, and in view thereof the material and the fuel are introduced at the lower portion of the kiln, so that the flame is upwardly directed. The invention will be more fully

described with reference to the accompanying drawing showing by way of example an upright kiln or shaft furnace embodying the principles of the invention.

60 In the drawing Figure 1 is a vertical section through the kiln on the line 1-1 of Figure 3. In Figure 2 a vertical section through the kiln or furnace is shown on the line 2-2 of Figure 1; Figure 3 is a horizontal section on the line 3-3 of Figure 1, and Figure 4 is a horizontal section on the line 4-4 of Figure 2.

65 The shaft of the kiln is indicated at *a*, and *b* is the dust chamber communicating with the heating channels *c*, *c* extending back and forth, as shown, *d* and *e* are the containers for coal dust and crude meal of the material respectively, *f* is a high pressure fan or blower; *g* is the burning nozzle, *h* is a short tube for the admission of the preheated air of combustion into the calcining shaft, *i* are chutes along which the burnt material is adapted to slide down into the delivery device *k*. Then, *l* is the suction pipe, *m* and *n* are the pressure tubes of the fan or blower *f*; *o* is a self-acting valve or damper, *p* is another blower or fan, *q* indicates another dust chamber, *r* and *s* are two conveyor 70 screws, *t* is a dredger or the like, *u* is a closing slide, *v* are two drying drums for the crude material, *w* is the chimney, *x* is a conveyor chute for the burnt or calcined material, *y* is a low pressure fan or blower, and *z* is the fresh air damper or valve.

75 The members *a*, *b* and *c* are jacketed and their interior walls at the points of the highest generation of heat consist of highly refractive clay or bricks, at the other points of ordinary "chamotte" or clay, while the outer walls are made of well insulated brick masonry or concrete masonry. Between the two walls there is a space for the circulation of the air of combustion. The air enters 80 through the adjustable valve or damper *z* by the action of the chimney; it flows through the space between the walls and is thereby highly heated. The air is finally delivered through the tubing *h* into the calcining shaft *a*. The preheating of the air 85 is carried on continuously in this manner and always remains uniform with a given size of heating surface and a given amount of fuel admission. Coal dust, oil or gas and crude meal of material are injected from below into the shaft *a* through the nozzle *g* and by means of the blower *f*, while a small 90

portion of the air of combustion is sucked in by means of the pipe conduit *l*. In order to control the quantity and temperature of the air to be aspirated the slide *A* and *5* the fresh air valve or damper *B* are provided and in order to avoid damaging the iron fan or blower it is necessary to keep the temperature of this small portion of the air of combustion below a certain limit.

10 The mode of operation of the apparatus is substantially as follows:—

The particles of material (arrows 1) having been carried up and calcined up by the flame have thereby acquired a higher specific *15* gravity and drop down along the walls of the shaft *a* (arrows 2) and proceed by way of the chutes *i* to the delivery device, or gate *k*, adapted to prevent the entrance of outer air into the shaft. The particles of calcined *20* material drop from the gate *k* into a shaking chute or channel *x* or into a similar device whence they are carried away for further treatment. The particles of material, however, which have not been completely calcined are carried by the suction *25* of the chimney into the dust chamber *b* (arrows 3) where they drop to the bottom, and become accumulated until their weight is sufficient to open the valve or closure *o* *30* sufficiently to allow them of being acted upon by the fan or blower *p* by means of which they are blown into the second dust chamber *q*. In this chamber they are caused to settle, preferably by electric means, and are *35* collected and are continuously conducted to the crude meal container *e* by the conveyor screws *r*, *s* and the dredger *t*, and may then be burnt over again. By this means it is *40* not only possible to avoid all losses of dust of material, but there is the further advantage that the finest particles of dust can be agglomerated.

For the purpose of recovering the waste *45* heat of the finished product a pressure pipe *n* is branched off from the pressure pipe *m*, said branch pipe *n* being adapted to lead an adjustable fraction of the air of combustion sucked in by the pipe *l*, through the glowing and completely calcined particles and to extract *50* the excess of heat therefrom. This highly heated portion of the air passes under the combined aspirating action of the chimney and of the nozzle into the shaft *a*. The regulation is effected by means of the damper or valve *C*.

The gases of combustion pass according to *55* the arrows 4 from the dust chamber *b* through the connecting tube *D* into the system of channels *c*; in case they should still be of a temperature exceeding the temperature necessary for keeping up the chimney draft, the gases, as appears from the drawing may be led through the drums *v* where the crude material is dried.

60 For the occasional cleaning of the system

of channels *c*, which is likely to become necessary, a low pressure ventilator or fan *y* is provided which, with the slide or damper *u* in the closed position and with the high pressure blower *f* out of operation, and with the valve or damper *o* opened, is adapted to blow the accumulated remnants of flue dust back from the channels *c* and *D* and into the chamber *b* where they are aspirated by the blower *p* and are thereby carried into the *75* second dust chamber *q*.

The entire arrangement of kiln with accessories operates in a perfectly automatic manner, after it has been once adjusted for a certain quantity of fuel found by experience *80* to be the proper amount, and with substantially unchanging size of flame and degrees of temperature of the heat of combustion. It should also be mentioned that the kiln or furnace may also be provided with inclined *85* shafts instead of with a vertical shaft, as herein shown by way of exemplification only, and it should be understood that other changes and modifications may occur in accordance with the particular requirements of *90* the varying conditions of application of the invention and to suit the convenience of the operator, such changes not constituting any deviation from the principles and from the *95* scope of my invention, as defined in the claims hereunto appended.

I claim:—

1. In a calcining kiln for cement and the like a burning and calcining shaft, a single conduit for introducing solid cement material in finely divided condition, air and fuel from below into the bottom thereof, and substantially in an upward direction, means adapted to introduce secondary air into said bottom portion in close vicinity of the material-air-and-fuel introducing means, discharging means communicating with the bottom portion below the said fuel-air-and-material introducing means and a settling chamber communicating with the top portion of the shaft.

2. In a calcining kiln for cement and the like a burning and calcining shaft, chutes for the removal of the calcined cement material below said shaft, a high pressure blower, means connected with said blower and communicating with the bottom portion of said shaft for the admission of solid cement material in finely divided condition, fuel and air of combustion into said bottom portion, a branch conduit on the compression side of said blower communicating with the said chutes, discharging means communicating with said chutes, and a settling chamber communicating with the top portion of the shaft, and substantially adjacent therewith.

3. In a calcining kiln for cement and the like a burning and calcining shaft, a high-pressure blower and a tube, said tube being adapted for the introduction of solid cement

- material to the shaft chutes for the removal of calcined cement material from the shaft, means for said jackets, and communicating with the jackets of the shaft and of said chutes being arranged below the shaft and communicating with the bottom portion thereof, chutes connecting said tube to the compression side of said blower, an air-introducing suction pipe on the blower and a delivery pipe on the blower connected to the bottom of the shaft and receiving means for fuel and solid cement material on said delivery pipe.
4. In a calcining kiln for cement and the like a jacketed burning and calcining shaft, a jacketed settling chamber, communicating with the top portion thereof, air admitting
- means between the jackets of the shaft and of the chamber, air heating passages below the shaft and the chamber and communicating with the jackets and with the bottom of the shaft means adapted to deliver finely divided material under treatment and fuel into the bottom portion of the calcining shaft a high pressure blower communicating with said delivering means and with an air supply, and discharging means in the bottom portion of said shaft.
- In testimony whereof I have signed my name to this specification.

CARL NASKE.
